UNITED STATES PATENT OFFICE.

WILLIAM L. CLOUSE, OF TIFFIN, OHIO. ASSIGNOR TO THE NATIONAL MACHINERY CO.,
OF TIFFIN, OHIO.

EJECTING ATTACHMENT FOR HEADING MACHINES.

1,412,844.

Specification of Letters Patent. Patented Apr. 18, 1922.

Application filed February 2, 1920. Serial No. 355,618.

To all whom it may concern:

Be it known that I, WILLIAM L. CLOUSE, a citizen of the United States, residing at Tiffin, in the county of Seneca and State of Ohio, have invented a new and useful Ejecting Attachment for Heading Machines, of which the following is a specification.

This invention relates to an attachment for heading machines. It has been the practice heretofore to provide means operated by a cam for ejecting bolts or rivets after being headed, such a construction adding materially to the cost of the machine in that it has required the use of shafts, rollers, rods and other mechanism for transmitting motion from a cam on the main shaft of the machine to the ejector at the other end of said machine.

One of the objects of the present invention is to provide ejecting mechanism which is of simple construction and is operated directly from the heading slide of the machine whereby an article is ejected immediately after each formation of a head thereon.

With the foregoing and other objects in view which will appear as the description proceeds, the invention consists of certain novel details of construction and combinations of parts which will be hereinafter more fully described and pointed out in the claims, it being understood that various changes may be made in the construction and arrangement of the parts within the scope of the appended claims.

In the accompanying drawings the preferred form of the invention has been shown.

In said drawings

Figure 1 is a plan view of a portion of a heading machine showing the present improvements applied thereto.

Figure 2 is a plan view of the ejecting attachment showing the ejecting rod retracted during the formation of the head.

Figure 3 is a similar view showing the positions of the parts after ejecting an article.

Figure 4 is an elevation of the structure shown in Figures 2 and 3.

Referring to the figures by characters of reference 1 designates the bed of the machine on which is mounted a heading slide 2, driven by a crank shaft 3 and provided with a heading die 4. A stationary die 5 is located on the bed at one end of the path of movement of the heading die and is adapted to cooperate with a movable gripping die 6 carried

by a gripping slide 7 operated in any desired manner. A stationary shear 8 is located to receive the stock as it is fed to the dies 5 and 6, said shear 8 and the die 6 cooperating to sever the stock into lengths. 60

A bracket 9 is extended from the bed 1 and has an upstanding pin 10. On the lower portion of the pin is fulcrumed a bell crank lever 11 while upon the upper portion thereof is fulcrumed a lever 12 one arm of which is connected by a rod 13 to the slide 2 while the other arm is preferably arcuate and is connected by a toggle 14 to one arm of the bell crank lever 11. A clamp 15 is pivotally mounted on the other arm of the bell 70 crank lever and grips an ejecting rod 16 which is slidably mounted in the shear 8 and carries a spring 17 one end of which bears against said die while the other end bears against the lever 11. The toggle 14 extends over another bracket 18 extending from the bed 1 and on this bracket at opposite sides of the middle joint of the toggle are studs 19 and 20. 75

It will be apparent that when the heading 80 slide 2 is moved forward toward the article between the gripping dies 6 and 5 it will thrust through rod 13 against the lever 12 and cause said lever to pull on the toggle 14 and lever 11 which in turn withdraws the 85 rod 16 from between said gripping dies. When the toggle is thus drawn it comes against the stud 20 so that the intermediate pivot of the toggle is thrust slightly past the dead center where the relative movement 90 of the links of the toggle is stopped by cooperating portions on the links in the form of shoulders or the like. As the heading slide moves away from the gripping dies it pulls through rod 13 upon the lever 12 95 which thus thrusts through the toggle against the lever 11 and causes the rod 13 to move against the shaped article and eject it. Just as the lever reaches the limit of its movement the middle joint of the toggle 100 comes against the stud 19 which breaks the joint in the toggle and allows the spring to expand and buckle the toggle as shown in Figure 3, thereby withdrawing the rod 16 to its set position. 105

What is claimed is:

1. In a heading machine the combination with a heading slide, of a lever connected to and actuated by the heading slide, an ejecting member, a lever connected thereto, 110

- a connection between the levers for transmitting motion from one lever to the other to move the ejecting member to active position, means for automatically shifting said connection upon the completion of the said movement of the ejecting member, and means for automatically returning the ejecting member to its normal position after the shifting of said connection.
- 10 2. In a heading machine the combination with a heading slide, separate levers, and a rod connecting said die with one of the levers, of an ejecting member connected to the other lever, a toggle connection between the levers, and separate means for straightening and breaking the toggle during successive strokes of the heading die.
- 15 3. In a heading machine the combination

with a heading slide and a spring restrained ejecting member, of separate levers, a rod connecting one of the levers to the heading die, a pivotal connection between the other lever and the ejecting member, a toggle connection between the levers, and separate means in the path of the intermediate joint 20 of the toggle for successively straightening the toggle and breaking the joint thereof during successive strokes of the heading die.

In testimony that I claim the foregoing as my own, I have hereto affixed my signature 25 30 in the presence of two witnesses.

WILLIAM L. CLOUSE.
